UNITED STATES PATENT OFFICE.

WILLIAM B. LAWRENCE, OF NEW YORK, N. Y., ASSIGNOR OF ONE-HALF TO
ALFRED A. MCCREARY, OF SAME PLACE.

SHADE OR REFLECTOR FOR ELECTRIC LIGHTS.

SPECIFICATION forming part of Letters Patent No. 416,682, dated December 3, 1889.

Application filed July 10, 1886. Renewed August 2, 1888. Again renewed May 21, 1889. Serial No. 311,504. (No model.)

To all whom it may concern:

Be it known that I, WILLIAM B. LAWRENCE, a citizen of the United States, and a resident of New York, in the county of New York and 5 State of New York, have invented certain new and useful Improvements in Shades or Reflectors for Electric Lamps, of which the following is a specification.

My invention relates to an improvement in 10 adjustable shades or reflectors for use in connection with all classes of electric lamps; and the object of the same is, by means of a revolvable and adjustable shade or screen made of any variety of opaque or translucent mate- 15 rial, and of such shape that it will conform to and fit closely over the globe or glass used upon the lamp, to produce any desired effect with the light, such as a peculiar color, a given direction, and an increased illuminating-power, according to the particular purpose for which the lamp is employed, by merely changing or revolving the shade or reflector.

My invention, which consists in applying to 25 a lamp a shade or reflector of the above character, and in providing certain mechanism for adjusting the same, will be best understood by reference to the accompanying drawings, in which—

30 Figure 1 shows the invention applied to the ordinary form of incandescent lamp. Fig. 2 is a view showing the manner of attaching the shade and the lamp. Figs. 3 and 4 are views of details of the manner of attaching 35 the lamp and the shade, and Fig. 5 shows the shade or reflector applied to the ordinary form of arc lamp.

Similar letters have reference to similar parts throughout the several views.

40 In the drawings, A represents the globe of an incandescent or arc lamp, which is attached in any convenient manner.

In Figs. 1, 2, 3, and 4, of which the former shows the incandescent lamp and the three 45 latter the manner in which the shade is attached, the globe A, Fig. 1, fits into a sleeve B, Figs. 2 and 3, which contains the light-wires a a. The sleeve B in turn fits into the socket D, Fig. 2, on the bracket, to which the 50 light-wires are applied, and is held in position and attached by means of the shoulder-pins d d, Figs. 2 and 3, fitting into the groove d' on the interior of the socket.

S is the shade, which is made to conform in shape as nearly as possible to the shape of the globe A, and to fit closely over the same, as shown in Fig. 1, and which may be arranged so as to encircle any desired portion of the globe; but in practice a shade which will surround from one-third to one-half of the globe will be found most advantageous. In the views, the shade is arranged to screen or cover one-half of the lamp-globe, and it terminates at the end at which the lamp is attached in a circular neck E, of sufficient diameter to enable it to slide loosely around the socket D, into which the sleeve B of the lamp fits, as shown in Figs. 1 and 2. For the purpose of holding the shade in any desired position on the lamp, the method of attachment 65 shown in Figs. 1, 2, and 4 is provided. In these views m m represent any number of flat springs arranged around the socket D, the same being fastened at one extremity by the screws o o to a sliding ring n on the 70 socket, so that when the shade S is placed over the socket D the springs m m will press upon the interior of the circular neck E of the shade and hold it fast. The ring n is broken at any one point and at the point of 75 juncture is provided with the flanges k k, through which the screw p passes. The ring n can be placed at any convenient point on the socket D by loosening the screw p and sliding the ring to the point desired and then 80 tightening the screw.

To remove the shade, it is only necessary to turn the globe A in the socket and unloosen and remove it, and then to pull the shade or reflector S over the extremity of the springs 85 m m, which are within the neck, and thus release the same. The incandescent lamp and the reflector S having been thus removed together from the socket, the globe or bulb A is then lifted out of the shade S, the larger portion being drawn out first and the sleeve B emerging last from the neck E. To adjust a shade, the globe is loosened from the socket and the globe pushed, sleeve first, into the shade S. The neck of the shade is then pushed 90 over the springs, and the sleeve B passes between them and into the socket D. By rotating the globe and shade on the sleeve until the pins d d catch in the seats, as before, the former is made fast and the latter will 95 have already been caught and held by the 100 105

springs. To adjust the globe, the extremities of the springs are compressed by the hand and the neck of the shade forced over them, and the globe then inserted in the same manner as it is withdrawn.

Any other method of attaching the shade may be adopted that will permit of its being readily removed and easily adjusted at any convenient plane to the lamp.

Fig. 5 shows one of the many forms of arc lamps, and is designed to show what is termed the ordinary "single-carbon" Brush lamp. In this view *c* and *c'* are the candles and *e* the socket which supports the lower candle *c'*; *f f*, the supporting-arms; *F*, the frame of the lamp, and *A* the globe. As in the other views, the shade *S* is made to conform in shape, as nearly as possible, to the globe *A*, and terminates in a neck *E*, as before, which encircles the socket *e* and is held in position by means of the springs *m*, attached, as before, to the ring *n*, which is adjustable upon the socket *e* in the same manner as in the case of the incandescent lamp shown in the previously-described figures. Any other convenient means of mounting and holding the shade *S* may be resorted to, provided that it admits of easily removing and adjusting the same.

The shade *S* may be made of any desirable material, according to the purposes for which it is used, and owing to the fact that it conforms so closely in shape to the lamp-globe as to become practically an outer covering to the same the color, direction, or intensity of the light will be changed, modified, or controlled, according as the shade or reflector is changed or rotated. Any variety of shades may be employed, made of any desirable material, and they may be changed or substituted from time to time, according to the purpose for which the light is used. Where it is desired to give any particular color or tint to the light, the shade may be made of glass, opaque or translucent, or of porcelain, of the particular color or tint desired. Where it is desired to have the shade serve principally as a reflector, it may be made of polished metal, or metal on glass coated with mercury, gold, or silver, and where it is desired to give a variegated color to the light shades of iridescent or opalescent glass may be used.

In case the shade is to be used upon the electric lamps in libraries or reading-rooms it will be found preferable to make them of white porcelain of thickness such as will allow the light to pass through it. The intensity of the light may then be instantly diminished by so rotating the shade that the same shall come between the globe of the lamp and the reader. To produce concentration or reflection of the light in any given direction, or for totally cutting off the same, metallic shades would ordinarily be used. The shades may be fitted to any of the ordinary forms of incandescent or arc lamps now in use without any further expense than the

cost of the shades and holders and the mere fitting of the latter to the lamp, and by having a selection of shades of different character or color a variety of different and strikingly-beautiful effects may be produced with an ordinary electric light.

Owing to the simplicity of the invention and its great cheapness the shades may be readily replaced from time to time as they get broken or bent at a comparatively small cost.

I claim as my invention—

1. The combination, with the globe of an electric lamp, of a revoluble and adjustable shade or reflector conforming in shape to the globe, fitting closely around a part of the same, substantially as hereinbefore set forth, by which means shades of different colors or reflectors can be employed interchangeably, and by revolving the latter the direction and intensity of the light can be changed or modified at pleasure.

2. The combination, with the globe of an electric lamp, of a revoluble and adjustable shade or reflector conforming in shape to the globe and fitting closely around a part of the same, provided at its extremity with a circular neck fitting over the socket of the lamp, substantially as hereinbefore set forth, by which means shades of different colors or reflectors can be employed interchangeably, and by revolving the latter the direction and intensity of the light can be changed or modified at pleasure.

3. The combination, with the globe of an electric lamp, of a revoluble and adjustable shade or reflector conforming in shape to the globe and fitting closely around a part of the same, substantially as hereinbefore set forth, made of porcelain, glass, metal, or other material, and provided with a neck formed integrally therewith, fitting over the socket of the lamp, a sliding ring upon said socket provided with springs pressing on the exterior of the neck of said shade for holding the same in any position, and means, substantially as described, for adjusting said ring vertically upon the socket.

4. The combination, with the globe of an electric lamp, of a revoluble and adjustable shade or reflector conforming in shape to the globe of the lamp and fitting closely over a part of the same, arranged to be removed and replaced by a similar shade or reflector of different material or color, substantially as hereinbefore set forth, by which means shades of different colors or reflectors can be employed interchangeably, and by revolving the latter the direction and intensity of the light can be changed or modified at pleasure.

Signed at New York, in the county of New York and State of New York, this 9th day of July, A. D. 1886.

WILLIAM B. LAWRENCE.
